(57) **CLAIM**

The ornamental design for a package for ammunition, as shown and described.

DESCRIPTION

U.S. Design patent application Ser. Nos. 29/503,546, 29/503,545, 29/503,535 and 29/503,553 filed on Sep. 26, 2014 are hereby incorporated by reference in their entirities.

FIG. 1 is a front perspective view of the package for ammunition, showing the first embodiment of our new design; FIG. 2 is a front view of the first embodiment of the package for ammunition;

FIG. 3 is a rear view of the first embodiment of the package for ammunition;

FIG. 4 is a right side view of the first embodiment of the package for ammunition;

FIG. 5 is a left side view of the first embodiment of the package for ammunition;

FIG. 6 is a top view of the first embodiment of the package for ammunition;

FIG. 7 is a bottom view of the first embodiment of the package for ammunition;

FIG. 8 is perspective view of the first embodiment of the package for ammunition holding ammunition;

FIG. 9 is a front sectional view of the first embodiment of the package for ammunition holding ammunition;

FIG. 10 is a front perspective view of the package for ammunition, showing the second embodiment of our new design;

FIG. 11 is a front view of the second embodiment of the package for ammunition;

FIG. 12 is a rear view of the second embodiment of the package for ammunition;

FIG. 13 is a right view of the second embodiment of the package for ammunition;

FIG. 14 is a left view of the second embodiment of the package for ammunition;

FIG. 15 is a top view of the second embodiment of the package for ammunition;

FIG. 16 is a bottom view of the second embodiment of the package for ammunition;

FIG. 17 is a perspective view of the second embodiment of the package for ammunition holding ammunition; and,

FIG. 18 is a front sectional view of the second embodiment of the package for ammunition holding ammunition.

In the drawings, the broken lines are for the purpose of illustrating environment only and form no part of the claimed design.

1 Claim, 14 Drawing Sheets
